UNITED STATES PATENT OFFICE.

CARL A. NELSON, OF CHICAGO, ILLINOIS, ASSIGNOR TO WESTERN ELECTRIC COMPANY, INCORPORATED, OF NEW YORK, N. Y., A CORPORATION OF NEW YORK.

PROCESS OF AND MACHINE FOR REMOVING COMBUSTIBLE COVERING

1,351,186.

Specification of Letters Patent. Patented Aug. 31, 1920.

Application filed March 2, 1917. Serial No. 152,016.

To all whom it may concern:

Be it known that I, CARL A. NELSON, a citizen of the United States, residing at Chicago, in the county of Cook and State of Illinois, have invented certain new and useful Improvements in Processes of and Machines for Removing Combustible Coverings, of which the following is a full, clear, concise, and exact description.

10 This invention relates to an improved process of and machine for removing combustible coverings, and more particularly to a machine of this kind for stripping insulation from the ends of insulated conductors 15 and the like.

One of the objects of this invention resides in an improved process of and machine for removing a combustible covering from a non-combustible article.

20 Another object of the invention consists in an improved machine for stripping insulation from the end of a conductor by first burning a groove or slot around the insulation covering and then stripping the severed 25 insulation end from said conductor.

Other objects of the invention will become apparent from the following description and the appended claims.

The preferred embodiment of the invention herein illustrated and described consists of a machine for removing the insulation covering from insulated cords, wires, etc., said insulation consisting of any combustible matter, preferably cotton, silk, or rubber, or 35 any combination thereof. In the operation of the machine a strip of metal having a high electrical resistance is electrically heated and revolved about the insulation covering of the cord or wire whereby a 40 groove or slot is burned in said covering and the insulation severed at this slot. The severed portion of the insulation is then readily stripped from the conductor.

According to the old method, insulation 45 of this character was removed from conductors by severing the insulation covering by means of a knife or any other sharpened edge and then stripping the insulation from the conductor. This method had two dis- 50 tinct disadvantages. First, the operator in cutting the insulation would very frequently cut into the conductor, thereby nicking the same; and second, when a cotton or silk insulation covering was thus severed, the ends 55 thereof were quite likely to unravel and the

frayed ends of this insulation frequently interfered with subsequent operations, such as soldering of the conductor proper and the like.

When the insulation is removed in accordance with this invention these difficulties are entirely eliminated and furthermore, the rate at which the insulation can be removed from the conductors is very materially increased, thereby greatly increasing the efficiency of this operation and reducing the cost thereof.

Obviously the invention is not limited to the specific embodiment herein described, but may be used whenever it is desired to remove from a non-combustible article a combustible coating with which said article is covered.

The invention is illustrated in the accompanying drawings in which:

Figure 1 is a front elevation of the complete machine;

Fig. 2 is an end elevation thereof;

Fig. 3 is an enlarged illustration of the burning element and its associated mechanism;

Fig. 4 is a section illustrating the method of mounting the current conducting disks;

Fig. 5 illustrates the position of the burning element as it is forced through the insulation on the wire, and

Fig. 6 is a circuit diagram illustrating the circuit connections.

The apparatus consists of a base 10 on which is mounted the upright 11 which supports a bearing 12 in which is journaled the shaft or spindle 13. Mounted on one end of the spindle is a pulley wheel 14, by means of which the shaft 13 may be rotated, and on the other end of said shaft is mounted the insulating disk 15 which carries the current conducting rings 16 and 17. The shaft 13 is fitted with a central bore in which is slidably mounted the rod 18 which carries the adjustment nut 19.

Secured to the base 10 is the block 20 composed of any suitable insulating material in which are mounted the current conducting strips 21 and 22 to which are secured the brushes 23 and 24 respectively which contact with the current conducting rings 16 and 17 respectively. Mounted on said disk 15 by means of the nut 25 is the rod 26 composed of a material having good electrical conductivity, such as copper, to 110

which is pivotally secured by means of the screw 27 the fork 28. Secured to the ends of the prongs of the fork 28 by means of the screws 29 and 30 and spanning the distance between said prongs is a strip of high resistance metal 31 composed preferably of platinum, nicrome, or the like.

Integral with the fork 28 and extending at substantially right angles thereto is the triangular lug 32 which contacts with one end of the slideable rod 18 and which serves to move said fork about its pivot 27 when the rod 18 is displaced toward the left, the fork and rod being returned to their normal position by a spiral spring 33, one end of which is secured to the disk 16 and the other end thereof to the fork 28. The prong 34 of the fork is in metallic contact with the rod 26; whereas the prong 35 of said fork is insulated from said rod and from the prong 34. The prong 34 is in electrical connection with the current conducting ring 17 by means of the rod 26 and the conducting plate 36 connected to said ring; and the prong 35 is connected to the conducting ring 16 by means of the conducting spring 37.

An upright 38 is mounted on the standard 10 to the left of the upright 11 and the block 20. This upright supports a clamping device 39 which is fitted with a conical groove 40, the center of which is in alignment with the axis of the rotating shaft 13, the clamping device being so mounted that when the fork 28 is displaced by the rod 18, the high resistance conductor 31 will just clear the inner surface of said clamping device when said high resistance strip 31 intersects the common axis of the shaft 13 and the conical groove of the clamping device. The clamping device is composed of two jaws, a stationary jaw 41, and a movable jaw 42 which is pivotally mounted by a screw 43 secured to the lower portion of the clamping device 39. A handle 44 integral with the movable jaw 42 is used to displace this jaw from normal, the jaw being returned to its normal position by the spring 45. The wire 52, from which the insulation is to be removed, is placed in a conical groove between the jaws 41 and 42 of the clamping device, from the inner face of which a length 47 projects from which the insulation is to be removed. The wire is held in this position by the straddling action of the said jaws whereby the reduced circumferential wall of said conical groove grips said wire. Secured to the upright 38 are the shields 55 and 56 which constitute side protecting walls for the clamping device and the forward end of the rotating fork and thus serve to protect the operator against accidents.

Heavy current carrying conductors 48 and 49 are connected to the conducting

strips 21 and 22 respectively, and these conductors are connected in a serial circuit with a rheostat 50 and a battery 51, or any other suitable current generating device. As shown in the circuit diagram, Fig. 6, the conductors 48 and 49 connect with the slip rings 16 and 17 respectively, the slip ring 16 being connected through the rod 26 and the prong 34 to one end of the resistance wire 31; the other end of said resistance wire being connected to the conducting strip 37, which is in turn connected to the second slip ring 17. Consequently when the movable member of the rheostat is adjusted to close the circuit, current will flow from the battery 51 through said rheostat to the wire 48, and thence through the current conducting ring 16, the rod 26, the prong 34, the resistance wire 31, the conducting strip 37, and finally by way of the conducting ring 17 and the conductor 49 back to the other side of battery. By suitably adjusting the movable member of the rheostat the current flowing in this circuit can be adjusted so as to obtain any desired degree of heat in the resistance strip 31.

In the operation of the machine, the adjustment nut 19 on the slideable rod 18 is first adjusted so as to give the desired amount of throw for the fork 28. The circuit of the rheostat is then closed and the current adjusted for the desired amount of heat, after which the wire is placed in the conical groove in the clamping device with the wire from which the insulation is to be removed extending from the inner surface of said clamping device. The shaft 13 is then rotated in any suitable manner, preferably by a belt attached to the pulley 14, which rotation will carry with it the fork 28 with its associated heated resistance element 31. While the fork is rotating, the slideable rod is moved to the left and the heated element 31 will impinge on the surface of the insulated conductor and burn a circular groove in the circumference thereof, the adjustment nut 19 being so placed on the rod 18 that the fork 28 will move through a distance which will be sufficient to cause the heated member 31 to burn through the insulation covering and not in any way affect the conductor 52.

When the heated element 31 has made several revolutions about the insulated conductor 46 and thereby burned a groove 53 therein, so as to sever the insulation covering, the slideable rod 18 is released and the fork 28 and the rod will return to normal. The operator will then extract the conductor from the clamping device by withdrawing the same from said clamping device in a direction substantially at right angles thereto. In this operation the small circular opening 54 in the inner end of said conical groove, due to the tension exerted by the spring 45,

will inclose the conductor 52, exposed by the circular slot burned in the insulation, and consequently as the wire is withdrawn from the clamping device, the inner face 5 thereof, due to this encircling of the conductor 52, will strip the severed end of the insulation from the end of said conductor. When the wire has thus been removed, another length thereof is inserted in position 10 in the clamping device and the above described operation is repeated.

The herein described method of removing insulation from wires and the improved machine for accomplishing the same is exceedingly beneficial, because the burning of the insulation results in a nice smooth even cut of said insulation and consequently does not expose any frayed ends. Likewise, as the movement of the burning member can be 15 readily adjusted, there is no danger of injuring the conductor due to contact between the conductor and said burning member. Further, since the operation of removing the insulation consists merely in clamping the 20 wire into position and then advancing the burning member, after which the wire can be withdrawn with the insulation removed, the operation is exceedingly rapid and very efficient.

30 Obviously the invention is not limited to the specific embodiment thereof which is herein illustrated and described, but is capable of many variations and applications without departing from its spirit and scope, as set forth in the appended claims.

What is claimed is:

1. In a device of the character described, in combination, a rotatable member, means for heating said member, and means for deflecting said member whereby it will impinge upon the surface of a combustibly coated article and burn a circumferential slot in said coating.

2. In a device of the character described 45 in combination, an article holding means, a rotatable member, means for heating said member, and means for deflecting said member whereby it will impinge upon the surface of a combustibly coated article held in said means and burn a circumferential groove in said coating.

3. A device of the character described 55 comprising in combination, means to hold a combustibly coated article whereby a short end thereof will protrude from one side of said means, a rotatable member, means for heating said member, and means for deflecting said member whereby it will impinge upon the said protruding combustible surface of said article and burn a circumferential groove in said coating.

4. A device of the character described 60 comprising in combination, straddling means serving to hold a combustibly coated article, a rotatable member, means for heating said member, and means for deflecting

said member whereby it will impinge upon a protruding end of said article and burn a circumferential groove in said coating.

5. In a device of the character described 70 in combination, a rotatable member, means for heating said member, means for deflecting said member, and adjusting means for regulating the amount of said deflection, said member when deflected contacting with 75 the surface of a combustibly coated article and thereby severing the continuity of said coating.

6. In a device of the character described in combination, a rotatable spindle, an insulating disk secured to said spindle, current conducting rings mounted on said disk, means pivotally secured to one face of said disk, a current carrying conductor associated with said means, current conducting means connecting said rings and said conductor, a source of current supply, straddling means for holding a combustibly coated article, and means to force said current carrying conductor against the combustible surface of a 90 protruding end of said article whereby a circumferential groove will be burned in said coating.

7. In a device of the character described in combination, a rotatable spindle, an insulating disk secured to said spindle, current 95 conducting rings mounted on said disk, means pivotally secured to one face of said disk, a current carrying conductor associated with said means, current conducting means 100 connected with said rings and said conductor, a source of current supply, article holding means comprising a yielding member which clamps said article in a fixed position and with a protruding end to be operated 105 on, means to force said current carrying conductor against a combustible surface of said protruding end whereby a circumferential groove will be burned in said coating and whereby when the article is withdrawn from 110 said holding means said protruding coating which extends beyond said groove is removed by said holding means.

8. In an insulating stripping machine, in combination, a rotatable member, means for heating said member, means for holding a 115 wire from which the insulation is to be stripped, means for deflecting said member so it will contact with the insulated surface of said wire and burn a circumferential slot in said insulation, and means whereby 120 the severed insulation will be stripped from said wire when it is withdrawn from said holding means.

9. In a device of the character described in combination, a rotatable member, electric 125 means for heating said member, and means for deflecting said member whereby it will impinge upon the surface of an inflammably coated article and burn a circumferential groove in said coating. 130

10. The process of removing a combustible covering from a non-combustible article, which consists in burning a circumferential groove in said coating thereby severing the continuity of said coating, and then stripping the severed coating from said article.
11. The process of removing a combustible covering from a non-combustible article, which consists in burning a circumferential groove in said coating by an electrically heated conductor thereby severing the continuity of said coating, and then stripping the severed coating from said article.
12. The process of removing a combustible covering from a non-combustible article, which consists in burning a circumferential groove in said coating by a rotating heated member thereby severing the continuity of said coating, and then stripping the severed coating from said article.
13. The process of removing a combustible covering from a non-combustible article, which consists in burning a circumferential groove in said coating by rotating an electrically heated conductor and thereby severing the continuity of said coating, and then stripping the severed coating from said article.
14. The process of removing a combustible covering from a non-combustible article, which consists in holding said article with a yielding contacting member, burning a circumferential groove in said coating, and then withdrawing said article from said holding member and stripping said coating from said article by the action of said yielding member.

In witness whereof I hereunto subscribe
my name this 22nd day of Feb., A.D. 1917.

CARL A. NELSON.
